United States Patent Office.

JOSEPH SEDGEBEER, OF PAINESVILLE, OHIO.

Design No. 3,390, dated February 23, 1869.

DESIGN FOR A GRINDING-MILL.

The Schedule referred to in these Letters Patent and making part of the same.

To all whom it may concern:

Be it known that I, JOSEPH SEDGEBEER, of Painesville, in the county of Lake, and State of Ohio, have produced a new and original Design for Iron Grinding-Mills; and I do hereby declare that the following is a full description of the same, reference being had to the annexed engraving, showing the said design in perspective.

The configuration represented by the engraving consists of the hopper A, square tube B, circular plate C, band-wheel or pulley D, and foundation E, the gene-

ral form and arrangement being more clearly shown in the engraving than can be described by words.

What I claim, and desire to secure by Letters Patent, is—

The design for grinding-mill shown in the engraving.

This specification, signed and witnessed this 2d day of February, 1869.

JOSEPH SEDGEBEER.
